UNITED STATES PATENT OFFICE.

WILLIAM RICHARD CONNOR, OF NEW YORK, N. Y.

DESIGN FOR A BROUGHAM-BODY.

SPECIFICATION forming part of Design No. 19,352, dated October 15, 1889.

Application filed September 11, 1889. Serial No. 323,670. Term of patent 8½ years.

To all whom it may concern:

Be it known that I, WILLIAM RICHARD CONNOR, a citizen of the United States, residing at New York, in the county and State 5 of New York, have invented and produced a new and original Design for Brougham-Bodies, of which the following is a specification, reference being had to the accompanying drawing, forming part thereof.

10 One view is all that is deemed necessary to fully illustrate my design.

My design consists of the line A, which is the face-line of the boot, curving upward as it leaves the toe-line of the bracket, until at the 15 point *a* the curve is reversed and continued until it reaches the seat-frame; also, of the rear boot-line B, curving upward and forward to the seat-frame, the bracket or toe-board of the boot with the inclination, as shown, con-

20 sisting of the top line, being straight and at an angle to the base-line of the boot, and the bottom line of the same being curved and terminating in the scroll, as shown. The wheel-house or arch line of the boot consists of a 25 regular curve from its beginning at the rear end of the base-line of the boot to a point that would intersect the base-line of the boot were it extended across to meet it. From thence to the base-line of the body it is extended by

30 a symmetrical and irregular curve.

The coupé-pillar C of the body in my design is made with its face-line *b* drawn verti-

cal and parallel with the front line of the door. The base-line of the body, commencing at a point back of the door and at the termination of the bottom quarter, is curved down and forward and continues with the curvature shown, and terminates with a scroll *c* at the front bottom point of the coupé-pillar C. 35

The back line in my design is one continuous curve, extending downward and forward with varying degrees of curvature until it intersects with the base-line of the body at its commencement. This back line forms the back line for the top quarter and the back and 45 bottom line of the bottom quarter of the body.

The other elements in my design consist in the enlarged area of the door-panel D, enlarged area of door-rail E, and the diminished area of glass-frame space F; also the arrangement of the vertical moldings G and H. 50

I claim—

The design for a brougham-body herein shown and described, the same consisting of the lines A and B and the arch or wheel-house line and bracket, as shown, the coupé-pillar line *b*, and back and base lines of body, also the enlarged surfaces D and E, and the diminished area F, with the arrangement of moldings G and H, as shown and described. 60

WILLIAM RICHARD CONNOR.
